UNITED STATES PATENT OFFICE.

THOMAS BARTON EASBY, OF BROOKLYN, NEW YORK, ASSIGNOR TO NEW YORK STAMP-ING COMPANY, OF BROOKLYN, NEW YORK, A CORPORATION OF NEW YORK.

DESIGN FOR A DISH-COVER.

52,564.

Specification for Design.

Patented Oct. 15, 1918.

Application filed June 28, 1918. Serial No. 242,496. Term of patent 14 years.

To all whom it may concern:

Be it known that I, THOMAS BARTON EASBY, a citizen of the United States, residing at Brooklyn, in the county of Kings and State of New York, have invented a new, original, and ornamental Design for Dish-Covers, of which the following is a specification, reference being had to the accompanying drawing, forming part thereof.

The figure is a plan view of a dish cover, showing my new design.

I claim:—

The ornamental design for a dish cover, as shown.

THOMAS BARTON EASBY.
